PROCESS OF MAKING COUNTERS

Charles W. Bailey, Lynn, Mass., assignor to
 Stewart Bros., a copartnership consisting of
 John Hammond Stewart and Roland A.
 Stewart, Lynn, Mass.

Application August 30, 1935, Serial No. 38,546

6 Claims. (Cl. 12—146)

This invention relates to counter stiffeners or counters for shoes and consists in an improved product and a novel process of producing the same. After the counter blank has been skived it is the practice to crimp the straighter or lower edge of the blank in order to facilitate the formation of the inturned heel seat flange in the molded counter. In short counters there is no objection to crimping the entire lower edge from 5 one end of the counter blank to the other, because the crimped portion or zone of a short counter is all utilized in the flange. In long shank fitting counters, on the other hand, the forward corners of the counters are carried beyond the heel seat 10 flange and extend an appreciable distance into the shank of the shoe. Under these conditions crimped corrugations are not only unnecessary in the forward ends of the counter, but they may be positively objectionable in that they tend to show through the upper leather as a blemish in the 15 otherwise smooth surface of the shoe.

Various attempts have been made heretofore to obviate or minimize this trouble, as for example, by swinging the counter blank as it enters and emerges from the rolls of the crimping machine. This reduces the width of the crimped zone at both ends, but does not result in a uniform product and neither this nor any other of these expedients has proved to be of 20 commercial value.

The present invention solves the problem above discussed and makes available for the first time a shank fitting counter, adequately crimped throughout the curve of its inturned flange and having smoothly curved uncrimped ends adapted to be compactly incorporated in women's shoes of the finest workmanship and material without causing any surface irregularities.

In one aspect my invention consists in an improved counter blank skived about its margin and provided in its lower edge with a zone of corrugations terminating at a predetermined distance from each end of the blank and having smooth end portions projecting beyond this corrugated zone. In another aspect it comprises a molded counter made from such a blank and having a crimped inturned heel seat flange and forwardly extending uncorrugated ends, smoothly curved in conformity to the shank curvature 45 of the shoe in which it is to be used.

My invention includes within its scope a novel process of making the improved counter of my invention, the process being characterized by the step of skiving the margin of the blank, and 50 then, while the skived blank is gauged for the

skiving operation, crimping its lower edge in a zone of predetermined length and location.

In the manufacture of counters it has been customary to skive the marginal edges of the counter by passing the blank endwise between rolls, one of which is a matrix roll designed temporarily to distort successive portions of the blank as it is advanced to a straight edge knife. A continuous skiving is thus removed about the margin of the blank and this step imparts the 10 desired tapered edge characteristic to the counter. It is important to present the blank properly to the matrix roll for the skiving operation, and accurately to control the travel of the blank in passing therethrough. The presentation of the 15 blank is usually effected by automatic feeding mechanism operating in timed relation to the rotation of the matrix roll so that the proper portion of the irregular periphery of the roll shall always exactly engage the corresponding 20 area of the counter blank.

I propose to take advantage of these conditions by controlling the presentation of the skived counter blank to the crimping mechanism and governing the location of the crimped zone in 25 the counter by the rotation of the matrix roll. In this way the crimped zone may be located in the counter with a high degree of accuracy and with complete assurance of uniformity of treatment in handling the product on a basis of 30 commercial quantities.

The nature of the invention will be best understood and appreciated from the following description of a preferred embodiment thereof selected for purposes of illustration and shown in 35 the accompanying drawing together with a somewhat diagrammatic representation of one form of mechanism suitable for carrying out the process of the invention.

In the drawing:— 40

Fig. 1 is a plan view of a counter blank,

Fig. 2 is a conventional view of associated skiving and crimping mechanisms suitable for carrying out the process of my invention,

Fig. 3 is a view in perspective of a skived and crimped counter blank, and 45

Fig. 4 is a view in perspective of a molded counter shown in position upon a shoe conventionally indicated.

The molded counter of my invention is produced from a flat counter blank 10, such as that shown in Fig. 1, which may be die cut from sheet leather board or other suitable composition in sheet form. The blank herein shown is provided with a small notch in its lower edge 50 55

to indicate the center of the counter and with other notches in the same edge which indicate the style or size of the counter or a point of reference for a subsequent shoe-making operation.

It will be understood that the counter blank as originally produced is of substantially uniform thickness throughout and that it is necessary first to reduce the thickness of its marginal edges about the entire periphery of the blank in order that the finished counter may be incorporated in the shoe smoothly and without creating ridges therein. In Fig. 3 is illustrated a counter blank as it appears after the skiving operation. A central elongated portion 12 only remains of the thickness of the original blank and the entire margin is reduced to substantially a feather edge by a long bevel cut.

The flat skived counter blank may now be crimped at its lower edge in an intermediate zone 14 which is spaced at either end a predetermined and appreciable distance from the ends of the counter. The blank thus presents smooth, tapered end portions 16 lying entirely outside the crimped zone 14 and which are to form the oppositely disposed forward ends of the molded counter. The present invention contemplates a counter blank crimped in this manner by any suitable process although a preferred process of carrying out the crimping step will be presently described.

Having produced a skived and crimped counter blank of the character shown in Fig. 3 the molding operation may then be carried out with the assistance of any suitable commercial counter molding machine or machines. In the molding operation the counter blank is brought into the characteristic U shape with its sides smoothly curved both longitudinally and transversely and with its forward end portions oppositely arranged in spaced relation. The margin of the counter blank is molded inwardly forming an in-turned heel seat flange 20 defined about the rear portion of the counter by a sharp vertex line which is the counterpart of the heel seat line of the shoe. In Fig. 4 the completed molded counter is shown in position upon or within a shoe indicated conventionally in dot and dash lines, and it will be apparent that the crimped zone in the flange 20 is confined to the heel seat portion of the counter and does not extend forwardly beyond the heel breast line. The two forward ends of the counter may, therefore, be molded smoothly into conformity to the smoothly curved shank portion of the shoe, and this contributes in the finished shoe to maintain the smooth, fine lines of the last.

Referring now to Fig. 2, I will proceed to explain one form of mechanism whereby the novel process of my invention may be satisfactorily carried out. This mechanism includes a stationary table 30, upon which is mounted a magazine 31 for containing a vertical stack of counter blanks 10 arranged in horizontal position. Successive counter blanks are removed from the bottom of the magazine by a reciprocating feed slide 32 which is actuated by mechanism partially shown in Fig. 2 but which needs no specific description.

At the left hand end of the table 30 is mounted the skiving mechanism which comprises a toothed feed roll 33, a cooperating matrix roll 34 and a stationary straight edge splitting or skiving knife 35. The toothed feed roll 33 is pressed yielding upwardly at all times in or-

der to conform the counter blank to the matrix cavity of the roll 34 and the latter is so shaped as to force those parts of the blank which are to be reduced in thickness partially below the line of the knife 35. The relative location of the magazine and the matrix roll is predetermined and the operation of the feed slide 31 carefully timed with respect to the matrix, so that each portion of the advancing blank is properly acted upon by the matrix surface and the desired shape imparted to the blank. In other words, the position of the blank is carefully gauged for the skiving operation.

As the skived counter blank 12 passes beyond the skiving knife 35, it is engaged by a pair of supplementary rolls 36 and 37 and advanced to the crimping mechanism. This comprises a lower corrugated roll 38 mounted in fixed bearings, and an upper corrugated roll 39 mounted upon bearings carried by a pair of pivoted arms 40, one of which is shown in Fig. 2. The arms 40 and the upper roll 39 are moved normally downwardly by a strong tension spring 41 and both rolls are driven in a counterwise direction by mechanism not shown. Associated with the lower roll 38 is a gauge roll 42 and associated with the upper corrugated roll 39 is a rotary cam 43 which runs upon the gauge roll 42, and positively determines the vertical position of the upper roll. The cam 43 is driven through a sprocket chain 44 and sprocket wheels, not shown, in fixed timed relation with respect to the matrix roll 34. The construction is such that the advancing end of the skived counter blank 12 reaches the crimping rolls while the upper roll is held by the cam 43 spaced from the lower roll and in inoperative position. The end of the counter is accordingly advanced between the two corrugated rolls without any crimping action until the drop in the cam 43 becomes operative. When this occurs the upper corrugated roll 39 is lowered and becomes immediately effective to corrugate the lower edge of the blank as its progress between the crimping rolls continues. The corrugated zone 14 is thus produced and its length is determined by the length of the low concentric portion of the cam 43. When the blank has been advanced to the end of the corrugated zone, the cam 43 again lifts the upper crimping roll 39 and the remainder of the counter blank is run through without crimping.

It will be apparent that the mechanism above described makes available one set of instrumentalities for skiving the margins of a counter blank and, while the blank is located or gauged as determined in accordance with the skiving operation, crimping a predetermined zone in a selected portion of the counter. The operation of the mechanism is entirely automatic and may be carried out at high speed and with extreme accuracy. The novel process of my invention is, however, in no sense limited in its practice to this or to any specific mechanism.

Having thus described my invention, what I claim as new and desire to secure by Letters Patent of the United States is:—

1. The process of making counters, which consists in skiving the margins of a counter blank and, while the blank is located as determined in accordance with the skiving operation, crimping a predetermined zone in its lower edge.

2. The process of making counters, which consists in skiving the margins of a counter blank and, while the blank is located as determined

in accordance with the skiving operation, crimping in its lower edge a zone of predetermined length spaced from both ends of the counter.

3. The process of making counters, which consists in moving a counter blank endwise and skiving its margins, and then, in the same endwise movement of the counter, crimping an intermediate portion of its lower edge in a location determined in accordance with the skiving operation.

4. The process of making counters, which consists in rolling a counter blank and skiving its margins, crimping a limited intermediate portion of its lower edge while the blank is located as determined in the prior skiving operation, and then molding the blank so that the crimped portion of its edge is included in the inturned flange while the forward ends of the molded counter present smoothly curved surfaces.

20 5. The process of making counters, which includes the steps of moving a counter blank endwise first through skiving instrumentalities to

skive a predetermined portion of the blank and then through crimping instrumentalities to crimp a lesser portion of the blank, maintaining continuous control of the blank, and limiting the action of the crimping instrumentalities to a portion only of the counter blank which has been skived by the skiving instrumentalities.

6. The process of making counters, which includes the steps of moving a counter blank endwise and continuously through skiving instrumentalities to skive a predetermined portion thereof and then through crimping instrumentalities to crimp a lesser portion of the blank, maintaining continuous control of the blank, skiving one edge of the blank from end to end in its passage through the skiving instrumentalities, and limiting the action of the crimping instrumentalities to perform a crimping operation on an intermediate portion only of the skived edge of the blank.
